United States Patent Office

Des. 185,708
Patented July 21, 1959

185,708

DRESSER OR THE LIKE

Ernest Herrmann, South Norwalk, Conn.

Application February 28, 1958, Serial No. 49,856

Term of patent 3½ years

(Cl. D33—6)

FIG.1

FIG. 4

Fig. 1 is a top plan view of a dresser or the like, designed in accordance with this invention;

Fig. 2 is a front elevation viewed along the line 2—2 of Fig. 1;

Fig. 3 is a side elevation viewed along the line 3—3 of Fig. 2; and

Fig. 4 is a front perspective view thereof.

I claim:

The ornamental design of a dresser or the like, as shown.
